UNITED STATES PATENT OFFICE

JAMES ROY AULENBACK, OF WORCESTER, MASSACHUSETTS

BORING TOOL

Application filed May 18, 1928. Serial No. 278,821.

This invention relates to improvements in boring tools and has for an object the provision of a tool of the hand operated type which may be quickly and readily set at various angles relative to the work and its holder and which will maintain the bar and tool carried thereby against chattering and springing out of proper position.

Another object of the invention is the provision of a boring tool which is capable of handling different types of bits and which is provided with means whereby a bit may be securely held in place, or readily removed and another bit substituted.

With the above and other objects in view, the invention further includes the following novel features and details of construction, to be hereinafter more fully described, illustrated in the accompanying drawings and pointed out in the appended claim.

In the drawings:—

Figure 1 is an elevation showing a fragmentary portion of a lathe with the invention applied.

Figure 2 is an enlarged longitudinal sectional view of the tool.

Figure 3 is an enlarged section on the line 3—3 of Figure 2.

Figure 4 is a similar view on the line 4—4 of Figure 2.

Figure 5 is an elevation of the bit carrying end of the tool.

Figure 6 is a fragmentary view partly in section illustrating a different type of bit.

Figure 7 is a similar view showing a different position of the bit.

Figure 8 is a like view showing a bit arranged at rightangles to the length of the bar.

Referring to the drawings in detail wherein like characters of reference denote corresponding parts, the reference character 10 indicates the tool post of a lathe and 11 the work holder.

The tool which is designed to be secured to the tool post comprises a bar 12 which is carried by a holder 13, the holder being arranged at an incline with respect to the bar and being adjustably mounted upon the tool post as shown at 14.

The bar 12 is cylindrical and is received within a split sleeve 15 which is carried by the holder 13. This sleeve is provided with an apertured ear 16 through which extends a stud 17. This stud has a threaded connection 18 with the end of the holder 13 and has pivotally secured to its outer end as shown at 19, an eccentric 20. This eccentric carries a handle 21, and by reference to Figure 4 of the drawings it will be seen that the eccentric may be operated to secure or release the bar 12 so that the latter may be longitudinally and rotatably adjusted upon the end of the holder 13.

The bar 12 is provided with a central longitudinally extending bore 22 having an enlarged portion 23 at one end. A tool receiving opening 24 intersects the outer end of the bore 22 and this opening may be arranged at a transverse incline as shown in Figures 2 and 7 of the drawings, while an additional rightangularly arranged opening 25 may also be provided. If desired a single rightangularly arranged opening 27 may be provided to receive a relatively flat bit 28 as shown in Figure 6, or a single similarly arranged opening 29 may be provided as shown in Figure 8.

The bore 22 is designed to receive a rod 30, one end of which is designed to grip the bit and for this purpose the bit may be notched as shown at 31 in Figure 6 of the drawing. The opposite end of the rod 30 is provided with a head 32 which is slidable within the enlarged portion 23 of the bore, while surrounding the rod 30 within this enlarged portion of the bore is a coiled spring 33. The spring 33 bears against the head 32 and against a shoulder at the inner end of the enlarged portion 23 of the bore 22 and acts to yieldingly force the rod away from the bit. This facilitates the insertion and removal of the bit as the end of the rod will be yieldingly held out of the opening 24.

The inner end of the bar 12 is provided with oppositely located longitudinally disposed slot 34 which receives the opposite edges of a flat clamping block 35. This block is adapted to be engaged within a notch 36 provided in the head 32 and by a set screw 37

whose inner reduced end is positioned within a slot 38 provided in the block 35. This screw 37 is of the headless type and its purpose is to hold the block against the head 32.

5 Threadedly mounted upon the inner end of the rod 12 is a cap 39. This cap engages the adjacent end of the block 35 and may be threadedly adjusted upon the rod to force the block inward so as to tightly engage the rod 30 with the bit and hold the latter in position. A handle 40 is carried by the cap for convenience of adjustment.

10 It will be apparent from the foregoing description and accompanying drawings that the tool will be rigidly held in position upon the tool post and the holder may be adjusted with respect to the post.

15 In addition, the tool may be adjusted within the holder so that the bit will be properly adjusted for the work. By removing the cap 39 and loosening the screw 37, the bit may be quickly removed and another bit of a similar or different type substituted.

20 The invention is susceptible of various changes in its form, proportions and minor details of construction and the right is herein reserved to make such changes as properly fall within the scope of the appended claim.

25 Having described the invention what is claimed is:

30 A boring tool comprising a bar adjustably secured to a holder and having a tool receiving slot at one end and a bore extending from the slot to the other end thereof and having a portion of the bore enlarged, a tool holding rod in said bore and engaging the tool in said slot, a notched head on the rod within the enlarged portion of the bore, a spring on the rod between one end of the enlarged bore and the head to normally urge the rod away from the tool, an adjustable cap threaded to the bar and closing one end of the bore, said bar having the last named end provided with slots, a block engaged by the cap and engaging in the notched head and slots of the bar, a set bolt carried by the bar and engaging the block to allow limited movement of the latter and covered by the cap, and a handle for said cap.

35 40 45 50 In testimony whereof I affix my signature.
JAMES ROY AULENBACK.
